UNITED STATES PATENT OFFICE

2,519,629

ELECTRIC CIRCUIT BREAKER

William George Bourne, London, England, assignor to Rotax Limited, London, England

Application November 6, 1947, Serial No. 784,357
In Great Britain October 30, 1946Section 1, Public Law 690, August 8, 1948
Patent expires October 30, 1966

5 Claims. (Cl. 200—122)

1

This invention relates to electric circuit breakers, and has for its object to enable a small breaker responsive to the heating action of an electric current to be provided in a simple and compact form.

The invention comprises the combination of a spring loaded snap-action lever mechanism carrying a contact and operable by either of a pair of push buttons, and a complementary contact carried by a thermally deformable member, the arrangement being such that the mechanism is also able to be actuated for separation of the contacts by deformation of the said member.

The invention further comprises the combination with a circuit breaker as specified in the preceding paragraph, of an additional pair of contacts arranged to be closed by actuation of one of the push buttons for short-circuiting at least part of the breaker to render the thermally deformable member inoperative.

In the accompanying drawings:

Figure 1 is a side elevation of an electric circuit breaker responsive to the heating action of an excess current constructed in accordance with the invention.

Figure 2 is a horizontal section taken on the line $x-x$ of Figure 1.

Figure 3 is a vertical section taken on the line $y-y$ of Figure 1.

In one convenient embodiment of the invention as illustrated in the drawings, there is provided a hollow body part or frame 1 which is preferably made as a moulding from insulating material. Within the body part is mounted a sheet metal frame 2, and on this frame is carried a bowed spring metal strip 3 having one end pivotally anchored to one end of the frame 2 at 4. The other end of the spring strip 3 is arranged to extend beyond a second pivotal anchorage on the frame provided by a bent strip 5 supported from a transverse pin 6 and having a forked end 7 which engages a pair of shoulders formed by cutting away side portions from the extreme end of the strip 3. Adjacent to this second anchorage there is provided on the frame a pivot pin 8 which supports a contact lever 9 carrying one of the contacts 10. A coiled spring 11 on the pin 8 has one end in engagement with the lever 9 and the other in engagement with a part 12 of the frame 2. The lever 9 also has a bent up portion 13 adjacent to the contact 10 which is adapted to engage a part of the bowed strip 3 between its anchorages. Further there is arranged in the body part 1 adjacent to the extended end of the bowed strip a coiled spring 14 having an integral 55

2

arm 15 projecting from one of its ends. Alternatively a spring loaded pivoted arm may be provided. The free end of the arm 15 is arranged to act on one side of the extended end of the bowed strip 3 and is movable by a push-button 16 which forms one of a pair slidably mounted in the front of the body part 1 (i. e. the top part as seen in Figure 1). The second push button 17 is loaded by a spring 18 and is arranged to act on a part of the strip 3 between the anchorages thereof, through the medium of the horizontal portion 19 of a lever 20 comprising a pair of parallel side portions pivotally mounted in the frame at 21. The bowed strip 3 is so arranged that its curvature is reversed when it is pushed through a central position from one limit to another. It is movable in one direction by the push button 17 and in the other direction either by the contact lever 9 or by the arm 15 associated with the push-button 16. One of the limit positions of the strip is determined by the abutment member 5 which is adjustable by means of the screw 22. An extension 23 of the frame 2 which passes to the exterior of the body part 1 has secured to it a terminal piece 23¹.

Within the body part and alongside the contact lever 9 is mounted a flat bi-metal strip 24 which is secured at one end to the body part and at its free end carries the complementary contact 25. This strip is connected to another terminal 26 on the exterior of the body part. The required thermal deformation of the bi-metal strip may be effected by the heating action of the current passing through it when the contacts are closed, but preferably a separate heating element is employed. This latter may consist of a resistance of any convenient form, but preferably it consists of a flat plate of metal 27 formed with parallel slots in staggered relation, the plate being mounted as shown in the body part adjacent to the side of the bi-metal strip 24 remote from the contact lever 9, and being connected in line with the bi-metal strip. Also at one side of the bi-metal strip 24 there is provided in the body part an adjustable abutment screw 28.

The arrangement is such that closing of the contacts 10, 25 is effected by the action of the push button 17 on the portion of the bowed strip 3 lying between the anchorages. This has the effect of reversing the curvature of the strip, causing it to assume the position shown by broken lines in Figure 1, and rocking the contact lever 9. Separation of the contacts is effected by the push-button 16 through the action of the arm 15 on the extended end of the

bowed strip 3, causing the deflection of this strip to be again reversed so that it returns to the upper position as seen in Figure 1.

So long as the current passing through the breaker is normal the heat generated in the heating element 27 and in the bi-metal strip 24 is ineffective, but an abnormal or excess current results in the bi-metal strip being deflected, and the pressure thereby exerted by this strip on the contact lever 9 causes the latter to actuate the bowed strip through the medium of the bent up portion 13 on the said lever and effect the sudden separation of the contacts.

For some purposes it is desirable to be able to reclose the contacts and hold them closed while an overload persists. To meet this requirement there are provided an additional pair of contacts which serve to short circuit the bi-metal strip or its associated heating element. In the arrangement shown a resilient metal blade 29 is secured to the frame 2 and carries a contact 30. This contact is adapted to co-operate with a complementary contact formed by a metal strip 31 connected to the contact 26. The blade 29 is movable for closing these additional contacts by one of the side portions of the lever 20 which is operable by the push-button 17. The arrangement is such that when the button 17 is actuated for closing the breaker, a slight additional movement brings the longer side of the said lever into engagement with the blade 29 and closes the contacts 30 and 31 so short circuiting the breaker, this condition being maintained so long as the additional contacts are held closed. On releasing the button 17 it returns sufficiently to allow the additional contacts to separate and so restore the normal working conditions of the breaker.

By this invention I am able to provide a small circuit breaker responsive to the heating action of an excess current in a very simple and compact form. The invention is not, however, restricted to the example described, as subordinate constructional details may be varied to suit different requirements.

Having thus described my invention what I claim as new and desire to secure by Letters Patent is:

1. An electric circuit breaker comprising in combination a pair of complementary contacts, an over-centre spring, a thermally deformable member carrying one of said contacts, a lever carrying the other of said contacts and responsive to opposite movements of said spring for opening and closing said contacts, a pair of push buttons arranged to act on said spring at different positions for causing opposite movements of said spring past a dead-centre position, and means whereby movement imparted to said lever through said contacts in response to deformation of said thermally deformable member can serve to move said spring in the direction for causing said contacts to open.

2. An electric circuit breaker comprising in combination a pair of complementary contacts, a bowed over-centre spring, a thermally deformable bi-metal strip carrying one of said contacts, a lever carrying the other of said contacts and responsive to opposite movements of said spring for opening and closing said contacts, a pair of push buttons arranged to act on the same side of said spring at different positions for causing opposite movements of said spring past a dead centre position, and means whereby movement imparted to said lever through said contacts in response to deformation of said bi-metal strip can serve to move said spring in the direction for causing said contacts to open.

3. An electric circuit breaker comprising in combination a pair of complementary contacts, a bowed over-centre spring, fixed and adjustable anchorages supporting said spring at positions spaced apart, a thermally deformable bi-metal strip carrying one of said contacts, a lever carrying the other of said contacts and responsive to opposite movements of said spring for opening and closing said contacts, a pair of push buttons arranged to act on the same side of said spring at different positions for causing opposite movements of said spring past a dead centre position, and means whereby movement imparted to said lever through said contacts in response to deformation of said bi-metal strip can serve to move said spring in the direction for causing said contacts to open.

4. An electric circuit breaker as claimed in claim 1 and having an additional pair of contacts arranged to be closed by movement of one of said push buttons beyond its normal operating position for short-circuiting at least a part of the breaker to render said thermally deformable member inoperative.

5. An electric circuit breaker as claimed in claim 1 and having a second lever through which one of said push buttons acts on said spring, an additional pair of contacts, and a spring blade carrying one of said additional pair of contacts, said blade being movable by said second lever in response to movement of the corresponding push button beyond its normal operating position, for short-circuiting at least a part of the breaker to render said thermally deformable member inoperative while the first mentioned contacts are closed.

WILLIAM GEORGE BOURNE.
